UNITED STATES PATENT OFFICE.

GEORGE S. BARROWS, OF PHILADELPHIA, PENNSYLVANIA, ASSIGNOR TO
THE WELSBACH LIGHT COMPANY, OF GLOUCESTER CITY, NEW JERSEY.

DESIGN FOR A MANTLE-SUPPORT.

SPECIFICATION forming part of Design No. 26,075, dated September 22, 1896.

Application filed May 26, 1896. Serial No. 593,185. Term of patent 14 years.

To all whom it may concern:

Be it known that I, GEORGE S. BARROWS, a citizen of the United States, residing at the city of Philadelphia, in the county of Philadelphia and State of Pennsylvania, have invented a new and original Design for Mantle-Supports, of which the following is a specification, reference being had to the accompanying drawing, forming part hereof.

The new, useful, and original shape or configuration for a mantle-support which comprises my invention or design is illustrated in the accompanying drawing.

The leading or characteristic feature of my design is a hook associated with a generally

upright body and shank, the whole constituting a complete mantle-support.

In the drawing, *a* is the hook; *b*, the body, *c*, the shank, and *a b c* the complete mantle-support. 20

What I claim is—

The design for a mantle-support, substantially as shown and described.

In testimony whereof I have hereunto signed my name.

GEORGE S. BARROWS.
